HAIR TWEEZERS

George T. Dale, Sea Cliff, N. Y.

Application November 22, 1950, Serial No. 197,149

1 Claim. (Cl. 128—354)

1
The present invention relates to improvements in tweezers and relates more particularly to tweezers especially adapted for plucking hairs or the like.

An object of the invention is to provide hair tweezers wherein the gripping portions of the tweezers are held in positive engagement with each other under spring pressure and the gripping action does not depend on the user holding the tweezers closed. In the present tweezers, the user merely releases whatever pressure is being exerted to hold the tweezers open and the user can then move the tweezers as desired by merely holding the handle. Another object of the present invention is to provide tweezers having gripping portions that are especially designed and adapted to grip small individual objects such as a human hair without disturbing or gripping surrounding objects. A further object of the invention is to provide a novel manner of securing the operating members of the tweezers together which permits the tweezers to be made at the lowest possible cost.

Other objects and advantages of the present invention will be apparent and best understood from the following description and the accompanying drawings in which:

Fig. 1 is a perspective view of hair tweezers embodying the present invention;

Fig. 2 is a side view of the hair tweezers illustrated in Fig. 1;

Fig. 3 is a plan view of the hair tweezers illustrated in Fig. 1 as seen from the rear;

Fig. 4 is a fragmentary side view of a portion of the hair tweezers illustrated in Fig. 1 but on an enlarged scale;

Fig. 5 is a fragmentary plan view of another portion of the hair tweezers illustrated in Fig. 1, but on an enlarged scale; and

Fig. 6 is a fragmentary view in section taken along the line 6—6 of Fig. 3.

Referring now to the drawings in detail, the tweezers consist of two operating members 10 which are formed from spring steel. The operating members 10 are identical with each other and they are preferably made of stainless steel or chrome plated to permit easy cleaning and to prevent them from rusting. This also gives the tweezers an attractive appearance.

Each of the operating members 10 has a blade or gripper 11 at one end thereof and a handle portion 12 at the other end thereof. The portion of the operating member 10 intermediate the ends is bent to form two arms 13 and 14 that extend outwardly at an angle from the gripper

11 and the handle portion 12, respectively, and join each other at an angle somewhat greater than a right angle.

The rear of the gripper 11 and a part of the arm 13 extending therefrom are notched along one edge, as indicated at 15, to a depth of at least one-half the width of the operating member 10. When the two operating members 10 are assembled, the arms 13 on the respective members are crossed with what would normally be the outer faces of the grippers 11 opposing each other. The arms 13 cross at the notches 14 at which point they are reduced in thickness so that they will not interfere with each other and the notches 15 also permit movement of the arms 13 with respect to each other.

When the operating members have been assembled, the handle portions 12 thereof are in opposing relation and they are secured together by a split sleeve 16. The split sleeve 16 is squeezed together and clamped to the operating members 10 after it has been put in place. When this is done, the operating members 10 are for all practical purposes permanently secured together without soldering or welding and any unsightly marring of the operating members as might occur if they were soldered or welded together.

The arms 14 extending from the handle portions 12 diverge in opposite directions from the point at which the handle portions are joined and they resiliently hold the opposing faces of the grippers 11 in firm, positive contact with each other. The arms 14 may be squeezed together by the user pressing against their outer sides and as indicated by the dotted lines in Fig. 2, this separates the opposing faces of the grippers 11 to engage the desired object. When pressure is released from the arms 14, the resiliency of the arms returns the grippers to their normal or gripping position without any other action on the part of the user.

As shown best in Fig. 5, the gripper portions 11 are pointed at their gripping ends and are beveled, as indicated at 17, along their side edges on one face thereof. The face of each of the gripper portions which opposes and contacts with the other gripper portion is flat. The manner in which the faces of the opposing gripper portions contact is shown in Fig. 4. This construction of the grippers permits small individual objects such as human hairs to be readily engaged with a sure, positive gripping action under the action of the spring arms 14.

It will be understood that various changes and

modifications may be made in the particular embodiment of the invention illustrated and described herein without departing from the scope of my invention as defined by the following claim.

I claim:

A tweezer comprising a pair of operating members made of spring steel, each of said members being identical and having a handle portion at one end thereof, said handle portions having opposing flat faces engaging with each other, opposing arms extending from said handle portions and diverging outwardly therefrom, a second arm extending inwardly from the outer ends of each of the first-mentioned arms, said second arms extending across each other and having elongated notches therein extending along the side edges thereof at the point where said arms cross, and a triangularly-shaped gripping member carried at the free end of each of said second

10

arms, said gripping members having opposed flat faces with the other faces thereof being bevelled along their side edges, said flat faces normally being held in resilient engagement with each other and a split sleeve extending over the handle portions of the operating members, said split sleeve being clamped together to hold the opposing faces of the handle portions in contact with each other.
